NECKTIE RACK

William R. Kohl, Glenview, and Arden L. Iverson,
Chicago, Ill., assignors to Para-Lux Products
Company, Chicago, Ill., a corporation of Illinois

Application January 25, 1947, Serial No. 724,400

10 Claims. (Cl. 211—89)

1

This invention pertains to an improved, flexible paper board or cardboard necktie rack adapted to be employed by cleaning establishments for the support of a plurality of neckties or like elongated articles of apparel during storage or delivery.

It is an object of the invention to provide a simple and inexpensive rack of the foregoing character which has provision for grippingly engaging a necktie or like article in a novel manner to positively resist displacement therefrom.

More specifically, it is an object to provide a rack of the above type which is apertured at spaced locations and provided with dual bendable supporting and locking tongues which are engageable with the article to secure the same in place on the rack in a novel and improved fashion.

The foregoing statements are indicative in a general way of the nature of the invention, but other and more specific objects will be apparent to those skilled in the art upon a full understanding of the construction and operation of the device.

A single embodiment of the invention is presented herein for purpose of exemplification, but it will be appreciated that the invention is susceptible of incorporation in other modified forms coming equally within the scope of the appended claims.

In the drawings,

Fig. 1 is a face view of the rack of the invention as stamped from a sheet of appropriate paper board or equivalent material;

Fig. 2 is a face view illustrating the rack with a plurality of neckties sustained and locked thereon, also indicating a suspending hook applied to the rack;

Fig. 3 is a view in vertical section, on a line generally corresponding to line 3—3 of Fig. 2, illustrating certain portions of the rack in the position to which they are displaced for the initial reception of the necktie or other article to be suspended on the rack;

Fig. 4 is a sectional view similar to Fig. 3, illustrating the elements of the rack in their operative locking relation to the article which is supported; and

Fig. 5 is a fragmentary perspective view fur-

2

ther illustrating the features of the invention.

This invention relates to a very simple and inexpensive cardboard necktie rack adapted to support elongated articles of apparel, such as neckties, belts and the like, during storage and transportation thereof. As distinguished from many similar articles on the market, in which the neckties are but loosely supported, hence capable of slipping from place under shocks and jostling, the present rack has novel coacting means for insuring that the article will be held in its initial desired, suspended position on the rack.

Referring to the drawings, the rack of the invention is generally designated by the reference numeral 10, being made up of a rack body 11, which is stamped from a sheet of a suitable gauge cardboard, paper board or like relatively inexpensive material, and a wire suspending hook, generally designated 12.

The uppermost edges 13 of the body 11 converge to a central apex, immediately beneath which the body is provided with a hole 14 and with a U-shaped slit 15, the upper extremities of which are connected with the hole by aligned crease or fold lines 16. This defines a tab 17 which is bendable upwardly onto the body 11 of the rack, as illustrated in Figs. 2 and 3, so as to afford a double-ply thickness of material at that point. Hanger 12 is shaped at its lower end to provide a U-shaped rack clamping element 18 insertable in the hole 19 from which the tab is deflected and engageable with the double-ply thickness to afford a very secure grip on the rack body 11.

Said body is provided with a plurality of rows of article engaging units, generally designated by the reference numeral 20, by appropriately slitting and creasing the material thereof. Each unit comprises an arm 21 integrally connected at one side thereof with the material of body 11, said arm being defined by an L-shaped slit 22 through the material of the rack and by a sawtooth slit 23 intersecting the righthand extremity of slit 22, in such manner as to provide an upwardly directed terminal lip 24 at said extremity. The opposite end of the sawtooth slit 23 is angled upwardly at 25 and the end thereof is connected with the extremity of lip 24 by a creased fold line 26. Accordingly, there is outlined the sawtooth

edged article-supporting arm 21, which is swingable on a vertically extending pivot adjacent its integral connection to the body 11 at the inner end of the arm, and a sawtooth edged article-retaining tongue 27 which is swingable along the horizontal, creased fold line 26, for the purposes to be described.

In the illustrated embodiment there are six of the units arranged in two horizontally extending rows of three each. However, it will be apparent that other arrangements either in the alignment of the rows or staggering of the units are possible.

In utilizing the rack, the necktie, designated N, is preferably doubled on itself and draped over an arm 21, which is deflected forwardly of the plane of rack body 11 for this purpose, as illustrated in Fig. 3. Arm 21 is then returned toward and beyond its original position in the plane of the body which causes tongue 27 to first swing rearwardly with the arm and then, as the necktie brushes beneath and past the same, to snap forward and crampingly engage the tie as illustrated in Figs. 4 and 5. This effects a very positive biting and clamping engagement with the article, sufficient to prevent dislodgment of the article from the rack under pronounced shocks. The position of the parts in the fully inserted condition of the article is illustrated in Figs. 4 and 5.

We are aware that necktie and related racks of various types have heretofore been proposed for a generally similar purpose. However, to our knowledge, none thereof embodies dual, coacting, article sustaining and anchoring elements swingable on pivots located in intersecting relation to one another, nor do any of the prior devices effect a comparably positive gripping and cramping action. We therefore desire that the invention be construed no more limitedly than is reasonably indicated by the scope of the appended claims.

We claim:

1. An article carrier of the type described, comprising a sheet-like body slitted and creased to provide supporting arm and clamping tongue elements swingable about non-parallel axes relative to the plane of the body, said elements having opposed portions located adjacent to and coacting with one another in gripping opposite sides of an article adapted to be disposed therebetween to clamp said article against inadvertent displacement from the carrier.

2. An article carrier of the type described, comprising a sheet-like body slitted and creased to provide supporting arm and clamping tongue elements swingable about non-parallel axes relative to the plane of the body, at least one of said elements having a serrated article engaging edge and the other thereof having a portion located adjacent to and coacting with said serrated edge in gripping opposite sides of an article adapted to be disposed therebetween to clamp said article against inadvertent displacement from the carrier.

3. An article carrier of the type described, comprising a sheet-like body provided with an article supporting arm swingable laterally relative to the plane of the body on a pivot extending in one direction and an anchoring tongue swingable relative to said plane on a pivot extending in another direction, said arm and tongue having opposed portions located adjacent to and coacting with one another in gripping opposite sides of an article adapted to be disposed therebetween to

clamp said article against inadvertent displacement from the carrier.

4. An article carrier of the type described, comprising a sheet-like body member slitted and creased to provide an integral article supporting arm swingable laterally out of the plane of the body member on a pivot extending in one direction and an anchoring tongue swingable out of the plane of said member on a pivot extending in another direction, said arm and tongue having opposed portions located adjacent to and coacting with one another in gripping opposite sides of an article adapted to be disposed therebetween to clamp said article against inadvertent displacement from the carrier.

5. An article carrier of the type described, comprising a sheet-like body member slitted and creased to provide an integral article supporting arm swingable laterally out of the plane of the body member on a pivot extending in an upward direction and an anchoring tongue swingable out of the plane of said member on a pivot extending in a sideward direction, said arm and tongue having opposed portions located adjacent to and coacting with one another in gripping opposite sides of an article adapted to be draped over said supporting arm to clamp said article against inadvertent displacement from the carrier.

6. An article carrier comprising a body of relatively thin flexible material, an article-sustaining arm integrally hinged to said body and swingable laterally in a sidewise direction out of the plane of the body, and an article-anchoring element located in adjacent opposed relation to said arm, said element being hinged to said body and swingable vertically relative to said body and sustaining arm into clamping engagement with an article adapted to be disposed across the latter.

7. An article carrier comprising a body of relatively thin flexible material, an article-sustaining arm integrally hinged to said body and movable laterally in a sidewise direction out of the plane of the body, and an article-anchoring element located in adjacent opposed relation to said arm, said element being integrally hinged to the body and movable relative to said body and sustaining arm into clamping engagement with an article adapted to be disposed across the latter.

8. An article carrier comprising a body of relatively thin flexible material, an article sustaining arm integrally hinged to said body and movable laterally in a sidewise direction out of the plane of the body, and an article-anchoring element located in adjacent opposed relation to said arm, said element being integrally hinged to the body and movable relative to said body and sustaining arm into clamping engagement with an article adapted to be disposed across the latter, said sustaining arm and anchoring element being provided with roughened edges engageable with opposite sides of said article to hold the same against displacement from the carrier.

9. An article carrier comprising a sheet-like body of flexible material provided with a pair of vertically spaced cuts, one of which defines a lower edge of an article clamping tongue and an upper edge of an article supporting arm, the other of said cuts defining the lower edge of said supporting arm, said cuts being connected at an end thereof to free said supporting arm for swinging movement in a generally horizontal direction out of the plane of said body, said tongue being swingable in a generally vertical direction about an axis spaced above the lower edge thereof.

10. An article carrier comprising a sheet-like

body of flexible material provided with a pair of vertically spaced cuts, one of which is of serrated outline and defines a serrated lower edge of an article clamping tongue and an upper serrated edge of an article supporting arm which is substantially coincident with said lower tongue edge, the other of said cuts defining the lower edge of said supporting arm, said cuts being connected at an end thereof to free said supporting arm for swinging movement in a generally horizontal direction out of the plane of said body, said tongue being swingable in a generally vertical direction about an axis spaced above the serrated lower edge thereof.
